DESIGN FOR A PIPE CUTTING TOOL

Carl H. Ingwer, Elyria, Ohio

Application July 9, 1945, Serial No. 120,572

Term of patent 14 years

(Cl. D54—13)

To all whom it may concern:

Be it known that I, Carl H. Ingwer, a citizen of the United States and a resident of Elyria, in the county of Lorain and State of Ohio, have invented a new, original, and ornamental Design for a Pipe Cutting Tool, of which the following is a specification, reference being had to the accompanying drawing, forming a part thereof.

Fig. 1 is a side elevational view of the pipe-cutting tool showing my new design; the handle being shortened by removing a section thereof;

Fig. 2 is a rear elevational view thereof; Figs. 3, 4 and 5 are sections taken from planes indicated by the arrows 3—3, 4—4 and 5—5 respectively.

The other side of the tool as viewed in Fig. 1 is substantially the same as the side shown.

I claim:

The ornamental design for a pipe cutting tool, substantially as shown and described.

CARL H. INGWER.
